UNITED STATES PATENT OFFICE.

JULIUS LUTZ, OF HEIDELBERG-NEUENHEIM, GERMANY.

OSCILLATING-CYLINDER PRINTING-PRESS.

No. 831,962.

Specification of Letters Patent.

Patented Sept. 25, 1906.

Application filed April 6, 1905. Serial No. 254,146.

To all whom it may concern:

Be it known that I, JULIUS LUTZ, director, a subject of the German Emperor, residing at Heidelberg-Neuenheim, Germany, have 5 invented certain new and useful Improvements in or Relating to Oscillating-Cylinder Printing-Presses, of which the following is a specification.

The present invention has reference to oscillating-cylinder printing-presses—that is to say, presses in which the impression-cylinder makes partial revolutions alternately in opposite directions and in fixed bearings, the invention having for its chief object to construct a power-driven prime or first form and inner or second form press which shall be double-acting. For this purpose the impression-cylinder is provided with two impression-surfaces which effect two prime or first 15 form impressions during the forward motion of the cylinder and of the traveling type-bed which has two corresponding impression-surfaces, two inner or second form impressions being obtained during the return motion.

25 In the drawings, Figure 1 illustrates diagrammatically a power-press in accordance with this invention, and Figs. 2 to 10 are diagrammatic views illustrating the operation of the press in accordance with this invention.

30 The type-bed *b* is provided with two form or impression surfaces *v* and *r*, the cylinder *a* likewise having two corresponding impression-surfaces 1 2 and 3 4. On both sides of the impression-cylinder *a* are arranged inking and distributing rollers *f* for inking the forms *v* and *r* during the forward and return movements of the bed.

Underneath the bed *b* in a known manner a rack is fastened, the teeth of which have not 40 been shown. With the rack a toothed wheel *B* meshes, and the said wheel *B* also engages a rack *C* at the bottom of the machine-frame. The teeth of the wheel *B* and rack *C* have not been shown. The toothed wheel *B* is connected, by means of a rod *D*, with a crank-wheel *E*, the latter being driven in a known manner by means of a toothed wheel fixed on the axis of a crank or fly-wheel. (Not shown.) While the crank *E* is rotating the 45 rod *D* is moved to and fro and causes a reciprocating movement of the bed *b*. As the foregoing manner of reciprocating the bed *b* is well known, it is thought unnecessary to show the same more than as illustrated in 50 Fig. 1.

55 Four grippers 1 2 3 4 on the impression-

cylinder *a* serve to alternately seize and release the sheets of paper. *c c'* are the cutter-cylinders which sever said sheets as they are fed from a continuous web 1, or said sheets 50 may be fed by hand. On the opposite side of the cylinder is arranged a turning-over device *d* of any well-known kind, which after the first impression turns the sheet over and feeds it to the pressure-surface of the bed to 55 be printed on its other side. The taking-off device *e*, also well known, conducts the perfected sheets to the piling or laying-on mechanism.

Referring to Figs. 2 to 10, Fig. 2 shows 70 the position of the impression-cylinder in the beginning of the forward movement; Fig. 3, in the beginning of the printing. Fig. 4 shows in which manner the second sheet (dash, three points) is seized by the 75 grippers. Fig. 5 shows the beginning of the first sheet (dash, point) being delivered to the turning-over device. Fig. 7 shows the position of the parts in the beginning of the backward movement. In Fig. 8 the turned- 80 over first sheet (dash, point) is seized by the grippers of the impression-cylinder. In Fig. 9 the first sheet is printed on its back side and delivered by the roller *e*, whereas the second sheet is seized by the grippers. In Fig. 10 85 the second sheet is printed on its back side and then delivered by the roller *e*.

The operation of the machine is as follows: After the type-bed *b* has commenced its forward travel the grippers 1 seize the sheets 90 which have been fed to them by the rollers *i* and severed from the web by the cutters *c c'* and lay it on the form lying on the pressure-surface *v* of the bed as it passes under the cylinder. After the printing said sheet is passed 95 on by means of feeding-out grippers *m* to the turning-over device in the well-known way. Meanwhile the grippers 3 seize the next sheet which is delivered at the point *i* and which is then printed on the form *r*, on which latter it 100 passes on to the turning-over device *d*. The bed and the impression-cylinder driven thereby have a forward motion of such length that the gripper 4 comes into action at the point of delivery *s* of the reversing device, 105 after which the return of the bed commences. At a proximate point the grippers 4 seize the first sheet as it is delivered by the turning-over device and lay it, blank side downward, on the form lying on *r*. By the time the gripper 2 reaches the point *s* the second sheet has 110 been turned over, so that it also is seized and

has its blank side printed on the form lying on *v*. Meanwhile the first sheet, printed on both sides, has reached the delivery device *e*, which delivers it to the piling or laying-on mechanism. On the further return motion the piling or laying-on of the second sheet takes place in similar manner.

The bed-motion and inking mechanism are similar to those of existing stop-cylinder presses.

Having now particularly described and ascertained the nature of my said invention and in what manner the same is to be performed, I declare that what I claim is—

- 15 1. An oscillating-cylinder printing-press comprising a reciprocatory bed having two forms, an oscillatory impression-cylinder oscillating in one direction during the forward travel of the bed and in the opposite direction during the rear travel of the bed, said cylinder provided with two impression-surfaces, gripping devices for retaining the sheets upon the cylinder when oscillating in both directions so that the sheets will be printed upon both sides, and a turn-over device for the said sheets printed on one side, combined with means for separating two sheets from a single web at each reciprocating movement of the bed, and for delivering said pair of sheets to the gripping devices.
- 20 2. An oscillating-cylinder printing-press comprising a reciprocatory bed having a plurality of forms, an oscillatory impression-cylinder oscillating in one direction during the forward travel of the bed and in the opposite direction during the rearward travel of the bed, and provided with impression-surfaces corresponding in number to the number of said forms, gripping devices for retaining a plurality of sheets upon the cylinder when said cylinder is oscillated in both directions so that the sheets will be printed upon both sides, and a turn-over device for the sheets that are printed on one side.
- 25 3. An oscillating-cylinder printing-press comprising a reciprocatory bed having a plurality of forms, an oscillatory impression-cylinder oscillating in one direction during the forward travel of the bed and in the opposite direction during the rearward travel of the bed, and provided with impression-surfaces corresponding in number to the number of said forms, gripping devices for retaining a plurality of sheets upon the cylinder when said cylinder is oscillated in both directions so that the sheets will be printed upon both sides, and a turn-over device for the sheets that are printed on one side, combined with means for separating a plurality of sheets from a single web at each reciprocating movement of the bed and then delivering said plurality of sheets to the gripping devices.
- 30 4. An oscillating-cylinder printing-press comprising a reciprocatory bed having a plurality of forms, an oscillatory impression-cylinder oscillating in one direction during the forward travel of the bed and in the opposite direction during the rearward travel of the bed, and provided with impression-surfaces corresponding in number to the number of said forms, gripping devices for retaining a plurality of sheets upon the cylinder when said cylinder is oscillated in both directions so that the sheets will be printed upon both sides, and a turn-over device for the sheets that are printed on one side.
- 35 5. An oscillating-cylinder printing-press comprising a reciprocatory bed having a plurality of forms, an oscillatory impression-cylinder oscillating in one direction during the forward travel of the bed and in the opposite direction during the rearward travel of the bed, and provided with impression-surfaces corresponding in number to the number of said forms, gripping devices for retaining a plurality of sheets upon the cylinder when said cylinder is oscillated in both directions so that the sheets will be printed upon both sides, and a turn-over device for the sheets that are printed on one side.

direction during the rearward travel of the bed, and provided with impression-surfaces corresponding in number to the number of said forms, gripping devices for retaining a plurality of sheets upon the cylinder when said cylinder is oscillated in both directions so that the sheets will be printed upon both sides, and a turn-over device for the sheets that are printed on one side.

3. An oscillating-cylinder printing-press comprising a reciprocatory bed having a plurality of forms, an oscillatory impression-cylinder oscillating in one direction during the forward travel of the bed and in the opposite direction during the rearward travel of the bed, and provided with impression-surfaces corresponding in number to the number of said forms, gripping devices for retaining a plurality of sheets upon the cylinder when said cylinder is oscillated in both directions so that the sheets will be printed upon both sides, and a turn-over device for the sheets that are printed on one side, combined with means for separating a plurality of sheets from a single web at each reciprocating movement of the bed and then delivering said plurality of sheets to the gripping devices.

In testimony whereof I have hereunto set my hand in presence of two subscribing witnesses.

JULIUS LUTZ.
